UNITED STATES PATENT OFFICE.

HECTOR GAWLEY, OF TACOMA, WASHINGTON.

STAMP-MILL.

1,201,717.

Specification of Letters Patent. Patented Oct. 17, 1916.

Application filed October 13, 1915. Serial No. 55,665.

To all whom it may concern:

Be it known that I, HECTOR GAWLEY, a citizen of the United States, residing at Tacoma, in the county of Pierce and State 5 of Washington, have invented certain new and useful Improvements in Stamp-Mills, of which the following is a specification.

The invention has relation to ore crushers and more particularly to the type of stamp 10 mills embodying a pestle adapted to be operated by gravitational action.

The invention relates more particularly to the instrumentalities whereby the pestle is reciprocated and at the same time rotated 15 whereby its crushing face is relatively changed to the anvil so as to cause all parts to wear uniformly.

The invention consists of a cam of circular form, an arm attached to the stem of the 20 pestle and arranged to travel upon the cam to impart a lifting of the pestle to the predetermined height, such arm being suddenly released to admit of the pestle falling rapidly so as to deliver a blow upon the ore or 25 other material to be crushed.

The invention further consists of an automatic feed which is adapted to be intermittently actuated by means of the arm arranged to travel upon the cam.

30 The invention furthermore consists of novel means for imparting rotation to the pestle, whereby the arm connected thereto is caused to travel upon the cam.

With these and other objects in view, my 35 invention will be more fully described, illustrated in the accompanying drawings, and then specifically pointed out in the claims which are attached to and form a part of this application.

40 In the drawings: Figure 1 is a view in elevation of a stamp mill embodying the invention, the cam and mortar being in section; Fig. 2 is a top plan view of the mill; Fig. 3 is a side view of the upper portion of 45 the stamp mill, showing more particularly the feed mechanism.

Corresponding and like parts are referred to in the following description and indicated in all the views of the drawings by the same 50 reference characters.

A suitable framework is provided for receiving and supporting the parts comprising the mill. This framework embodies a base 1, uprights 2, a cross piece 3 connecting the 55 upper ends of the uprights 2 and an intermediate cross piece 4. The mortar is mount-

ed upon the base 1 and comprises an anvil 5 and inclosing shells 6 and 7. The inner shell 6 projects to a height slightly above the upper face of the anvil 5 and is provided with an inwardly and downwardly inclined rim 8 which serves to direct the material to the anvil. The outer shell 7 is spaced a distance from the inner shell 6 and is provided near its lower end with a spout 9 for carrying off the crushed material. A screen 10 is attached at its lower end to the upper portion of the shell 6 and the material, when crushed sufficiently fine, passes through the meshes of the screen 10 into the space 70 formed between the shells 6 and 7 and passes off through the spout 9. The pestle 11 may consist of a pounder of any desired formation and is provided with a stem 12 which extends vertically and is mounted in the 75 cross pieces 3 and 4 so as to receive both a rotary and a reciprocating movement.

A spur gear 13 is fastened to the stem 12 and its teeth are in mesh with the teeth of a long pinion 14 which is journaled at 80 its ends in bearings provided upon the cross pieces 3 and 4. The axis of the long pinion 14 is parallel with the axis of the stem 12 so that the teeth of the gear wheel 13 will mesh uniformly with the teeth of the long pinion 14 in every adjusted position of the gear wheel. Rotary movement is imparted to the long pinion 14 and is transmitted therefrom to the pestle by means of the intermeshing gear wheel 13. The long pinion 90 14 may be driven from a source of power by any suitable means and, as shown, a drive shaft 15 mounted in bearings provided upon the cross bar 3 is provided at one end with a beveled gear 16 which is in mesh with a companion beveled gear 17 secured to the upper end of the shaft or journal of the long pinion 14. A band pulley 18 secured to the drive shaft 15, is adapted to receive movement from a suitable source of power 100 by means of a drive belt 19.

An arm 20 is secured to the upper portion of the stem 12 and is provided at its free end with a roller 21 which is arranged to travel upon a cam 22 which is secured to the cross piece 3 in any manner. The cam 22 is of circular formation and constitutes a track for the roller 21 to travel upon. One end of the cam 22 terminates abruptly and when the roller 21 clears the high end of the cam, the pestle drops a distance corresponding to the lift of the cam. 110

The rotation of the pestle imparts a corresponding rotary movement to the arm 20 and the roller 21 riding upon the cam 22 causes the pestle to gradually rise preliminary to delivering the next stroke when the arm 20 clears the high end of the cam 22. The weight of the pestle and the lift of the cam 22 determine the force of the blow delivered by the pestle when the mill is in operation.

The ore or other material to be crushed or pulverized is intermittently fed to the mill from a suitable source of supply, such as a hopper 23 which is conveniently disposed. A spout 24 leads the material from the hopper 23 and delivers the same to the mill. A valve 25, disposed in the spout 24, controls the delivery of the material. The valve 25 is intermittently actuated so as to deliver the material at predetermined intervals. A lever 27 is disposed with one end in the path of the roller 21 carried by the arm 20. The opposite end of the lever 27 is connected by any suitable means to the valve 25 for operating the same. The connection between the lever 27 and valve 25 is indicated at 28. While the lever 27 may be disposed in any manner, it is shown arranged with the end adapted to be engaged by the roller 21 at a point between the high and the low ends of the cam 22. The roller 21, in its travel from the high end of the cam to the low end, passes over the end of

the lever 27 arranged in its path and depresses such end, thereby effecting a corresponding lifting of the opposite end which is connected with the valve so as to operate the latter and admit of a certain amount of material passing into the mill. It will thus be understood that the valve is operated at each movement of the pestle so that fresh material is supplied for the next stroke of the pestle. The inclined rim 8 insures the material being directed to the anvil so that every part of the material is subjected to the pounding action of the pestle.

Having thus described the invention, what is claimed as new is:

A stamp mill embodying a rotary reciprocating pestle, a stationary cam concentric with the stem of the pestle, an arm extending from the end of the pestle and having its free end adapted to ride on the cam, and a feeder comprising a spout arranged to deliver material below and into the path of the pestle, a lever fulcrumed between its ends adjacent the cam and having one end projected under the cam into the path of the free end of the arm traveling thereover, a valve controlling the flow through the said spout, and a connection between the said valve and the lever.

In testimony whereof I affix my signature.

HECTOR GAWLEY. [L. S.]
